(57) **CLAIM**

The ornamental design for a cigar cutter, as shown and described.

DESCRIPTION

FIG. 1 is a front and top perspective view of a cigar cutter, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion indicated with numeric 9 in FIG. 5; and,

FIG. 10 is an enlarged view of a portion indicated with numeric 10 in FIG. 8.

The broken lines in the drawings depict portions of the cigar cutter that form no part of the claimed design. The dash dot dash lines in FIGS. 5, 8, 9 and 10 are for the purpose of depicting the boundary lines of the enlarged view and form no part of the claimed design.
